LIQUID DISPENSING AND LEVEL MAINTAINING DEVICE

Oscar H. Jung and Paul E. Heffelfinger, Milwaukee, Wis., assignors to Trico Fuse Manufacturing Co., Milwaukee, Wis., a corporation of Wisconsin

Application October 7, 1932, Serial No. 636,662

8 Claims. (Cl. 137—68)

This invention appertains to liquid supplying devices, and more particularly to a novel device which is especially susceptible for automatically maintaining the proper level of a liquid in a vessel 5 at the point of use, such as oil in a bearing, engine crank-case, etc.

One of the primary objects of our invention is to provide an oil supplying device of the reservoir or fountain type, with novel means for quickly adjusting the reservoir relative to the bearing or crank-case, as the case may be, whereby the desired quantity of oil can be supplied to the point of use and whereby the preferred height of oil in the bearing or crank-case can be maintained.

Another salient object of our invention is to provide means whereby the reservoir can be quickly adjusted to the desired height from the exterior thereof without the use of tools and without the necessity of removing the reservoir from the lubricator.

A further important object of our invention is to provide an oil lubricator embodying a removable reservoir or container for the oil mounted upon a supporting reservoir or cup having an adjusting screw axially associated therewith, novel means being provided for detachably coupling the reservoir or oil container with the screw, so that upon rotation of the reservoir the screw will be turned to hold the reservoir or container in the desired height.

A still further object of our invention is to provide an improved oil lubricator of the above character, which will be durable and efficient in use, one that will be simple and easy to manufacture, 35 and one which can be placed upon the market at a reasonable cost.

With these and other objects in view, the invention consists in the novel construction, arrangement and formation of parts, as will be hereinafter more specifically described, claimed and illustrated in the accompanying drawing, in which:

Figure 1 is a vertical section through the improved lubricator.

Figure 2 is a fragmentary side elevation of the supporting reservoir or cup.

Figure 3 is a horizontal section through the improved lubricator illustrating the means for detachably coupling the reservoir or oil container with the adjusting screw.

Referring to the drawing in detail, wherein similar reference characters designate the corresponding parts throughout the several views, the letter A generally indicates our improved lubricator, which comprises a supporting reservoir or

cup 5 which includes a cylindrical side wall 6 and a bottom wall 7. The bottom wall 7 at its axial center is provided with a depending nipple 8 and the side wall 6 adjacent to the bottom wall 7 is provided with a laterally extending outlet nipple 9. A feed pipe 10 can be associated either with the nipple 9 or the nipple 8 according to the particular type of bearing or the like with which the lubricator is associated. In the present instance, we have shown the feed pipe 10 connected with the nipple 9 and the nipple 8 is closed by a removable plug 11. This plug 11 also facilitates the cleaning of the apparatus. The nipple 8 has connection with the body portion of the cup 5 by means of ports 12 placed around the axially disposed threaded bore 13. This threaded bore 13 receives the adjusting or feed screw 14, for a purpose which will be later set forth.

Slidably and rotatably mounted upon the cup or supporting reservoir 5 is the adjusting shell 15 and this adjusting shell 15 includes a cylindrical side wall 16 and a top wall 17 which is flared inwardly toward its axial center, as shown in Figure 1. The central portion of the top wall 17 is provided with an inwardly directed threaded neck 18, for a purpose which will later appear.

Mounted upon the top wall 17 of the adjusting shell 15 is an oil container or reservoir 19, which is preferably formed from transparent material, such as glass. This container can be in the nature of a bottle and can be constructed after the conventional manners of bottles. This container is provided with an elongated neck 20 and the neck adjacent to its point of connection with the body of the container is provided with the exterior screw threads 21 for receiving the threaded neck 18 of the adjusting shell 15. The neck 20 preferably extends into the cup 5 a material distance and the extreme end of the neck carries spaced lugs or tits 22 for detachable engagement with the radially extending arms 23 of the adjusting head 24 rigidly connected with the inner end of the adjusting or feed screw 14.

From the construction so far, it can be seen that when the parts are disposed as shown in Figure 1 of the drawing, it is merely necessary to rotate the shell 15 which will carry the container 19 therewith. The engagement of lugs 22 with the arms 23 will rotate the adjusting or feed screw 14 feeding the screw inward or outward, as the case may be, according to the direction of rotation of the adjusting shell. Thus, this allows the quick and easy adjustment of the

container or reservoir 19 from the exterior of the device without the employance of tools.

Air channels 25 are formed in the outer face of the cup 5.

5 When it is desired to fill the container 19 with the oil, it is merely necessary to lift up on the shell and container and pull the same off of the cup or supporting reservoir 5 and the reservoir or container 19 is turned so as to dispose 10 its neck uppermost. Oil can now be readily poured therein and the shell and container can then be quickly returned to the supporting reservoir or cup 5. By this arrangement, it can be seen that the container can be quickly and 15 easily removed from the cup and placed back thereon and that the lugs 22 of the neck of the container will always be in proper position for engaging the arms 23 for the adjusting head 24.

In order to prevent the loss of oil from the 20 container 19 when the same is being placed back into the supporting reservoir or cup 5, a check valve 26 can be provided. When the container is raised above the adjusting head 24 of the feed screw, the valve 26 seats upon the neck. This 25 valve 26 can be provided with a stem 27, the lower end of which is adapted to engage the upper end of the feed screw when the parts are properly assembled so that the valve will be held above its seat to permit the flow of oil from the 30 container 19 into the cup. The container with its neck 20 can be built in any desired way to permit the association of the valve 26 therewith and if so desired, the valve can be placed in the container during the forming of the container.

If preferred, a set screw 28 can be adjustably 35 associated with the shell 15, so that after the shell and container have been adjusted to the desired height, the shell can be locked with the cup and thus, held against further rotation.

From the foregoing description, it can be seen that we have provided a novel and simple form 40 of lubricator in which the reservoir or container can be quickly adjusted to the desired height to suit varying conditions from the exterior thereof.

While in the above specification we have described the device for use particularly as a lubricator, it is to be understood that the principles of the invention are susceptible for general use, 45 wherever a liquid supply and level maintaining device is desired, such as in chicken feeders, air conditioners and moisteners, etc.

Changes in details may be made without departing from the spirit or the scope of this 50 invention, but what we claim as new is:—

1. A liquid dispensing and level maintaining device comprising a cup provided with an outlet, an adjustable support positioned in said cup, a liquid container slidably guided on said cup and having interlocking engagement with said support for effecting adjustment of the same upon rotation of the container.

2. A liquid dispensing and level maintaining device comprising a cup provided with an outlet, 65 an adjustable threaded support positioned in said cup movable toward and away from the upper end of said cup, a liquid container slidably and rotatably guided on said cup, and detachable interengaging means carried by the container and support whereby adjustment of the support can be had upon rotation of the container.

3. A liquid dispensing and level maintaining device comprising a supporting cup, an adjusting shell rotatably and slidably mounted upon said cup, a container connected with the shell having a depending neck received within the cup, an adjusting member in said cup, and means detachably connecting the neck with said adjusting member.

4. A liquid dispensing and level maintaining device comprising a supporting cup, an adjusting shell rotatably and slidably mounted upon the upper end of said cup, a container connected with the shell having a depending neck extending into the cup, an adjusting screw associated with the cup, companion couplings carried by 15 the neck and the adjusting screw, and means for locking the adjusting shell against movement relative to the cup.

5. A liquid dispensing and level maintaining device comprising a supporting cup, a shell slidably and rotatably mounted on the cup, a container detachably connected with the shell having a neck extending into the cup, a feed screw carried by the cup having a head formed on its upper end provided with radially extending arms, 20 and lugs formed on the neck for detachable engagement with said arms.

6. A liquid dispensing and level maintaining device comprising a supporting cup having a depending outlet nipple and a laterally extending outlet nipple, an adjusting screw having threaded engagement with the cup extending into the depending nipple, a head connected with the upper end of the screw provided with spaced radially extending arms, an adjusting shell rotatably and slidably mounted on the cup, a container connected with the shell having a neck extending into the cup provided with lugs for detachable connection with the arms of said head, and a check valve for the neck of said container.

7. A liquid dispensing and level maintaining device comprising a supporting cup having a depending outlet nipple and a laterally extending outlet nipple, an adjusting screw having threaded engagement with the cup extending into the depending nipple, a head connected with the upper end of the screw provided with spaced radially extending arms, an adjusting shell rotatably and slidably mounted on the cup, a container connected with the shell having a neck extending into the cup provided with lugs for detachable connection with the arms of said head, and a check valve for the neck of said container, said valve having a stem adapted to engage the adjusting screw when the neck is detachably coupled therewith.

8. A liquid dispensing and level maintaining device comprising a supporting cup, a container including a body and an elongated neck, an adjusting shell slidably and rotatably mounted upon the cup having an inwardly pressed top wall provided with a threaded neck, means for threading said threaded neck on the neck of the container, an adjustable member supported by the cup, and means for detachably coupling the container with said adjusting member.

OSCAR H. JUNG.
